UNITED STATES PATENT OFFICE.

EMERSON P. JENNINGS, JR., OF LEHIGHTON, PENNSYLVANIA.

OPERATING DEVICE FOR IMPRESSION THROW-OFFS.

1,279,873.

Specification of Letters Patent. Patented Sept. 24, 1918.

Original application filed March 30, 1916, Serial No. 87,725. Divided and this application filed September 25, 1916. Serial No. 121,945.

To all whom it may concern:

Be it known that I, EMERSON P. JENNINGS, Jr., a citizen of the United States, residing at Lehighton, in the county of Carbon and State of Pennsylvania, have invented certain new and useful Improvements in Operating Devices for Impression Throw-Offs, of which the following is a specification, reference being had therein to the accompanying drawings.

This invention relates to a device for operating the impression throw-off of a printing press, and the present application is a division of the application filed by me March 15 30th, 1916, Serial Number 87725.

In the operation of a printing press it is undesirable that the form should engage the make-ready on the platen, and to prevent this engagement when no paper has been placed in printing position, without stopping the press, it is customary to provide an impression throw-off by means of which one member of the printing couple can be moved from its normal position a distance sufficient to prevent the engagement of the two members thereof when they are brought into what would otherwise be their printing positions. The throw-off is usually manipulated by the operator but in the case of presses in which the paper is fed automatically, either in a web or in sheets, the operator does not watch the feeding of the paper closely enough to enable him to operate the throw-off in time to prevent the form from engaging the make-ready, and it is desirable that the throw-off should in such cases be automatically controlled.

The object of the invention is to provide means operated by a moving part of the press to automatically actuate the throw-off when no paper is fed to printing position; and further to provide such a device with means to automatically restore to its normal position that member of the printing couple which has been shifted.

It is also an object of the invention to provide such a device which will be sufficiently sensitive to enable it to be controlled by the paper which is being fed to the printing couple, and will be of a strong durable character and of such a construction as to render it highly practical for commercial use.

In the accompanying drawings Figure 1 is a side elevation of a printing press show-

ing my invention applied thereto; Fig. 2 is a side elevation of an enlarged scale of a portion of the press showing the invention applied thereto, and Fig. 3 is a sectional detail view of the actuating bar.

In these drawings I have illustrated one embodiment of my invention and have shown it as applied to a bed and platen press equipped with an automatic sheet feed, but it will be understood that this particular type of press and of feeding mechanism is shown for the purpose of illustration only.

The press here shown comprises the main frame 1 consisting of side members spaced apart and tied together by tie rods and connecting devices and serving to support the various parts of the printing and feeding mechanisms. A normally stationary platen 2 is mounted near one end of the press and a combined form bed and inking drum 3 is mounted for movement toward and from the platen. The combined form bed and inking drum is provided at its ends with trunnions 4 mounted in guide blocks 5 which are slidably mounted in guideways 6 formed in the side walls of the main frame 1. These trunnions are connected by pitmen 7 with crank wheels 8 which are here shown as gears meshing with pinions 9 mounted on a shaft 10 to which power may be applied in any suitable manner.

The press is provided with an automatic sheet feed consisting of a supporting device 11 for a pile of sheets and having means for separating the same, as shown at 12. Mounted at the sides of the platen are vertically reciprocatory bars 13 which are actuated from a moving part of the press and which carry conveying grippers 14 the movement of which is so timed that they will engage the separated edge of a sheet of the pile of sheets and draw the same from said pile and into printing position. The present separating device separates the lowermost sheet from the pile and this sheet is drawn from beneath the pile by the conveying grippers. This mechanism is fully illustrated and described in the above mentioned application and further description of the same would seem to be unnecessary to an understanding of the present invention.

The press is provided with throw-off mechanism adapted to move the platen toward and away from the form-bed, thus enabling it to be moved out of the path of

the form and to prevent an impression from being taken. This throw-off mechanism may be of any suitable character but that here shown is of the type shown and described in the patent to Cartwright, No. 1,069,764, of August 12th, 1913. The mechanism of the throw-off forms no part of the present invention and it is sufficient to note that it is provided with an operating handle 101 by means of which it is manipulated to impart movement to the platen. In order to automatically operate this throw-off I establish a connection between the handle 101 and a moving part of the press, such as one 15 of the slide blocks 5, which carry the form-bed. This connection is of such a character that when a sheet is fed to printing position the connection is inoperative and the throw-off mechanism is not actuated. However, 20 when no sheet is fed to printing position the connection becomes operative and the mechanism is actuated. Preferably, the connection comprises two members slidably connected, with a stop adapted to be moved into 25 and out of a position to interrupt the movement of one of the members and this stop is controlled by the paper which is being fed to the printing position. As here shown the connection comprises a telescoping rod, 30 one part, 102, of which is connected with the handle 101 and the other part, 103, of which is connected with a bracket 104 secured to the slide block 5 and has its inner end slidably mounted in the rod 102, which 35 is tubular. The relation of the two parts of the rod is such that when unobstructed the part 103 is free to slide in the part 102 throughout the movement of the slide block 5 and the form-bed. The tubular member 40 102, however is provided with a movable stop, and, as here shown, has in one side thereof an aperture 105 in which is slidably mounted a pin or stop 106. A boss 107 projects from the outer surface of the tubular 45 member in alignment with the aperture and co-operates therewith to form a guideway for the pin 106. The boss is provided with a set screw 108 which extends into a slot 109 in the side of the pin 106 and serves to 50 limit its movement. This pin is arranged to be actuated by a finger 110 rigidly secured to a shaft 111 which is rotatably mounted on the press, in the present instance, on the supplemental frame 13^a. An arm 112 is rigidly secured to the shaft 111 and extends 55 forwardly to a point between the platen and the sheet separating device, with its forward end arranged in such a position that it will be engaged by the sheet as it is withdrawn from the pile and moved downward, thus rocking the shaft 111 and causing the arm 110 to lift the pin 106 out of the path of the inner member 103 of the telescoping rod, thereby permitting this 60 member to have continued movement in the 65 member 102, and preventing the operation of the throw-off mechanism. However, if a sheet is not fed across the end of the arm 112 the stop will remain in the path of the inner member 103 of the connecting rod and will thus form a rigid connection between the two parts of the device which will cause the operation of the throw-off mechanism. The inner member 103 of the actuating rod is provided within the outer member 102 of that rod with a lug or shoulder 115 which is arranged to co-operate with a lug 116 carried by the outer member. The two lugs are so arranged that when no movement has been imparted to the actuating bar as a 70 whole, to operate the throw-off, the lug 116 will lie beyond the limit of movement of the lug 115. However, when the actuating bar has been operated to actuate the throw-off, the lug 116 will move toward the throw-off mechanism and upon the outward movement of the inner member 103, the lug 115 will engage the lug 116 and return the outer member 102 of the actuating bar to its normal position thus throwing on the impression. If desired, the inner member 103 may be provided with an extension 117 slidably mounted thereon and arranged to contact with the pin 106 and a cushioning spring 80 85 90 95 100 105 110 115 120 125 130

Having shown and described one embodiment of my invention, I wish it to be understood that I do not wish to be limited to the details of construction for various modifications will occur to a person skilled in the art.

Having thus fully described my invention, what I claim as new and desire to secure by Letters Patent is:—

1. In a printing press, a printing couple comprising a normally stationary member and a member movable toward and from said stationary member, means for feeding paper to said printing couple, throw-off mechanism to move said stationary member rearwardly from its normal position to throw off the impression, a normally operative actuating device for said mechanism, and a part operatively connected with said actuating device and arranged to be engaged

and actuated by the paper as it is fed to said printing couple to render said actuating device inoperative and to prevent the operation of said throw-off mechanism.

- 5 2. In a printing press, a printing couple, means for feeding paper thereto, mechanism to shift one member of said printing couple to throw off the impression, an actuating device for said throw-off mechanism 70
 10 comprising two parts connected respectively with said throw-off mechanism and with a movable part of said press, the two parts of said device being connected one with the other for relative longitudinal movement, 75
 15 means normally limiting the relative movements of the two parts of said device to cause said throw-off mechanism to be operated, and a part operatively connected with said means and arranged to be actuated by 80
 20 the paper as it is fed to said printing couple to move said means into an inoperative position. 85

3. In a printing press, a printing couple, means for feeding paper thereto, mechanism 25 to shift one member of said printing couple to throw off the impression; an actuating device for said throw-off mechanism comprising two overlapping parts connected respectively with said throw-off mechanism 90
 30 and with a movable part of said press, the two parts of said actuating device having movement relatively one to the other, a movable stop held normally in a position to limit the relative movement of said parts 95
 35 and thus establish an operative connection between said throw-off mechanism and said movable part of said press, and a device operatively connected with said stop and arranged to be actuated by the paper as it 100
 40 is fed to said printing couple to move said stop into an inoperative position.

4. In a printing press, a printing couple, means for feeding paper thereto, mechanism to shift one member of said printing couple 45 to throw off the impression, an actuating rod for said throw-off mechanism comprising two overlapping parts connected respectively with said throw-off mechanism and with a movable part of said press, the 105
 50 two parts of said actuating rod having movement relatively one to the other, a movable stop held normally in a position to limit the relative movement of said parts and thus establish an operative connection 110
 55 between said throw-off mechanism and said movable part of said press, and a device operatively connected with said stop and arranged to be actuated by the paper as it 115
 60 is fed to said printing couple to move said stop into an inoperative position.

5. In a printing press, a printing couple, means for feeding paper thereto, throw-off mechanism for one member of said printing couple, an actuating device for said throw-off mechanism comprising two overlapping 120
 65

parts connected respectively with said throw-off mechanism and with a movable part of said press, the two parts of said actuating device being capable of longitudinal movement relatively one to the other, 70 a movable stop held normally in a position to limit the movement of said parts of said actuating device in one direction to cause said throw-off mechanism to be operated, said parts of said actuating device having portions co-operating to limit their relative movement in an opposite direction and thus cause the throw-off mechanism to be moved in a direction to restore the impression, and a device operatively connected with said stop and arranged to be actuated by the paper as it is fed to said printing couple to move said stop into an inoperative position and thus prevent the operation of said throw-off mechanism. 80

6. In a printing press, a printing couple, means for feeding paper to said couple, throw-off mechanism for one member of said printing couple, an actuating rod for said throw-off mechanism comprising two telescoping parts connected at their opposite ends with said throw-off mechanism and with a movable part of said press, respectively, a stop movably mounted on one part of said rod and held normally in the path of the other part thereof, a finger pivotally mounted on said press, operatively connected with said stop and having a part arranged in the path of the paper as it is fed to said printing couple, whereby said finger will be 100 actuated by the paper to move the stop into inoperative position. 95

7. In a printing press, a printing couple, one member of which is movable toward and from the other, means for feeding paper to said printing couple, throw-off mechanism for one member of said printing couple, an actuating rod for said throw-off mechanism comprising telescoping parts, one of which parts is connected with the movable member 105 of said printing couple and the other of which parts is connected with said throw-off mechanism, a stop movably mounted on one part of said throw-off mechanism and held normally in the path of the other part 110 thereof to limit the movement of the one part toward the other, and means actuated by the paper as it is fed to said printing couple to move said stop into an inoperative position whereby the movement of the one part of said telescoping rod relative to the other part thereof is limited only by the movement of the movable member of the printing couple. 115

8. In a printing press, a printing couple, 120 means for feeding paper to said printing couple, throw-off mechanism for one member of said printing couple, an actuating rod for said throw-off mechanism comprising telescoping parts, one of which is connected 130

with said throw-off mechanism and the other of which is connected with a movable part of said press, a movable stop held normally in position to limit the movement of the last 5 mentioned part of said rod toward the other part and thus cause said rod to move as a whole and to actuate said throw-off mechanism, the two parts of said rod having coöperating lugs adapted to be brought into 10 engagement by the movement of the last mentioned part of said rod away from said first mentioned part thereof, to restore said throw-off mechanism to its normal position, and means actuated by the paper as it is fed 15 to said printing couple to move said stop into an inoperative position and thus prevent the operation of said throw-off mechanism.

9. In a printing press, a printing couple, 20 one member of which is movable toward and from the other, means for supporting a pile of sheets above said printing couple, feeding mechanism to carry a sheet of paper from said pile into a printing position between the 25 members of said printing couple, throw-off mechanism for one member of said printing couple, an actuating rod comprising overlapping parts connected respectively with said throw-off mechanism and with a movable part of said press, a stop to limit the relative movement of the parts of said actuating device in one direction to cause said throw-off mechanism to be operated, an arm pivotally mounted above said actuating device and connected with said stop, a finger connected with said arm and having one end extending into position between said sheet supporting means and said printing couple, whereby said finger will be engaged by the 35 sheet as it is fed from said pile to said printing couple and will be actuated to cause said stop to be moved into an inoperative position.

10. In a printing press, a printing couple 40 comprising a normally fixed member and a member movable in a right line toward and from said fixed member, means for feeding paper to said printing couple, throw-off

mechanism for one member of said printing couple, an actuating rod for said throw-off 50 mechanism comprising two telescoping parts connected respectively with a movable member of said printing couple and with said throw-off mechanism, a stop movably mounted on one part of said rod and held 55 normally in the path of the other part thereof to cause the two parts to move together and actuate said throw-off mechanism, and means actuated by the paper as it is fed to 60 said printing couple to move said stop into an inoperative position, and thereby permit the one part of said rod to slide within the other part thereof without operating said throw-off mechanism.

11. In a printing press, a printing couple 65 comprising a normally fixed member and a member movable in a right line toward and from said fixed member, means for feeding paper to said printing couple, throw-off 70 mechanism for one member of said printing couple, an actuating rod for said throw-off mechanism comprising two telescoping parts connected respectively with a movable member of said printing couple and with said throw-off mechanism, a stop movably 75 mounted on one part of said rod and held normally in the path of the other part thereof to cause the two parts to move together and actuate said throw-off mechanism, means actuated by the paper as it is fed to 80 said printing couple to move said stop into an inoperative position, and thereby permit the one part of said rod to slide within the other part thereof without operating said throw-off mechanism, and other stops carried by the two parts of said rods and arranged to be brought into operative engagement when the one part of said rod is moved away from the other after said throw-off 85 mechanism has been operated, and to cause 90 said throw-off mechanism to be restored to its normal position.

In testimony whereof I hereunto affix my signature.

EMERSON P. JENNINGS, JR.
